UNITED STATES PATENT OFFICE.

GEORGE WHEALE, OF MEADOWBROOK, PENNSYLVANIA.

DUST-PAN.

1,226,153.

Specification of Letters Patent. Patented May 15, 1917.

Application filed January 12, 1915. Serial No. 1,835.

To all whom it may concern:

Be it known that I, GEORGE WHEALE, a citizen of the United States, residing at Meadowbrook, in the county of Montgomery and State of Pennsylvania, have invented certain new and useful Improvements in Dust-Pans, of which the following is a specification.

This invention relates to dust pans or crumb trays and particularly to that class of dust pans or crumb trays which may be used with convenience by either a left-handed or right-handed person.

The object of the invention is the provision of a dust pan or crumb tray, the handle of which may be set at an angle from the body of the pan for the convenience of the user.

Another object of the invention is the provision of a device of this character which is so constructed as to have the movable handle set in the position desired when using the device.

With these and other objects of the invention which will appear as the description progresses, the invention consists of the simple arrangement of parts, durability, and cheapness of manufacture.

In the drawings:—

Figure 1 is a perspective view of the invention;

Fig. 2 is a central longitudinal section;

Fig. 3 is a plan of the blank from which the main body is formed;

Fig. 4 is a plan of the blank from which the handle is formed.

The dust pan or crumb tray may be constructed from any light metal or other durable material and the body portion 1 has side flanges or walls 2 which extend from the front edge of the pan to the semicircular rear portion 3 of the body. This rear portion 3 is bent upwardly as at 4 and extends rearwardly at an angle to the base 1, while soldered or brazed to the rear portion 3 is the hood 5 which is attached to the portion 3 of the pan so as to allow a flange 6 to extend outwardly around the edge of the hood, for a short distance therefrom.

The hood 5 is formed of a single sheet of blank material and the curved edge is soldered or brazed to the base so as to provide an arcuate opening for the hood.

The handle 7 is formed of a single piece

of blank material 8 as shown clearly in Fig. 4 which is provided with the slots 9. These slots 9 are arranged so as to come at diametrically opposite points on the handle when the blank is formed into the cylindrical form to constitute an efficient handle.

The rear portion 3 is provided with an opening through which is projected a pivot pin or bolt 10 extending also through an opening 11 in the extension 12 of the handle. As shown in Fig. 2, the head of the pivot pin or bolt 10 is in position adjacent the upward bend 4 so as to raise the pan at this point a slight distance above the front edge thereof. This is an important feature inasmuch as it greatly facilitates the brushing of crumbs or dust into the pan because the edge is always in close proximity to the article whereon the device is to be used.

The flange 6 is disposed in an arc around the edge of the hood 5 at the rear portion thereof and is arranged in the slot 9 of the handle in such a manner as to cause a tight and taut pull to be exerted by the pivot pin 10 on the handle against the flange 6 where the flange engages the end of the slot 9. From this construction it is apparent that the handle may be swung on its pivot and by virtue of the tight fit of the flange 6 in the slot 9 the handle will remain at any desired angle which can be conveniently used by either a right-handed or left-handed person.

What is claimed is:—

1. In a dust pan, the combination of a body, a handle having an extension projecting beneath the body and pivotally connected thereto so that the handle may move in a horizontal plane, and a flange on the body to maintain the handle in its plane.

2. In a dust pan, the combination of a body provided with upturned edges, a handle provided with a plurality of recesses, an extension formed on the handle, said extension being pivoted beneath the body whereby the handle may move horizontally, and a flange on the body received in the recess to guide the handle in its movement.

In testimony whereof I affix my signature in presence of two witnesses.

GEORGE WHEALE.
